UNITED STATES PATENT OFFICE

2,516,312

COOLING SYSTEM FOR INTERNAL-
COMBUSTION ENGINESEarl Ginn, North Muskegon, Mich., assignor to
Continental Motors Corporation, Muskegon,
Mich., a corporation of Virginia

Application June 28, 1945, Serial No. 601,981

3 Claims. (Cl. 123—171)

1

This invention relates to an internal combustion engine and has particularly to do with a novel engine design and cooling system therefor.

The problem of cooling internal combustion engines has been ever present since the introduction of such engines. Whether the cooling system is one involving use of air or water, constant efforts have been made to improve the effectiveness thereof.

It is an object of the present invention to provide a design for an internal combustion engine which not only may be more readily cooled but which in being so designed is more compact.

Another object of the invention is the provision of an air flow control to direct cooling air most advantageously to the portions of the engine needing cooling.

Other objects and features of the invention relating to details of construction and operation will be evident in the ensuing description and appended claims.

For a more detailed understanding of my invention, reference may be had to the accompanying drawings illustrating preferred embodiments of my invention, like parts of which are referred to by like characters throughout the specification and in which:

Fig. 1 shows an elevation of the flywheel side of a single cylinder engine and generator combination.

Fig. 2 is an elevation of the reverse side of the engine showing the driving wheel and a portion of the air shroud.

Fig. 3 is a plan view of the engine and generator combination.

Fig. 4 is an end view of the engine, and

Fig. 5 is a sectional view of the engine taken on the line 5—5 of Fig. 3.

A generator, the housing 10 of which is shown in Fig. 3, has pulley wheel 11 driven by belts 12 running from drive wheel 13. Drive wheel 13 is located on the end of crankshaft 14 of a single cylinder four stroke cycle internal combustion engine 15. The engine housing or crankcase 16 is suitably mounted on pads 17. A fuel tank 18 supplies gasoline to a carburetor 19. A magneto 20 suitably driven furnishes the ignition current for sparkplug 21.

A governor throttle control is shown at 22.

The finned cylinder 30 of the engine projects vertically above the crankcase 16. Valves 31 and 32 are intake and exhaust valves, respectively, mounted in the same casting with the power cylinder but it will be noted that the plane of the valves is perpendicular to the crankshaft as is

also the cam shaft 35 which drives the valves in a wormgear connection with the crankshaft.

The cylinder head 36 is likewise provided with parallel fins 37 extending across the cylinder in line with the crankshaft 14.

At the left end of crankshaft 14 (see Fig. 5) is a flywheel 40 having air driving blades 41. The flywheel end of the engine is shrouded by a formed housing 42 which has an air inlet opening 43. The housing projects upward and over the cylinder 38 passing around the cylinder fins at least 180 degrees in a portion 44. This leaves the opening shown in Figs. 2 and 4 for the outlet of air.

15 Within the shroud a diversion plate 48 is provided which terminates at the junction 49 of the valve housing and cylinder head 36. A guard 50 forms the other side of a passage A leading directly from fan wheel 40 past the valves 31 and 32. A passage B leads directly to the finned cylinder head where a volume of air passes before flowing down and out the opening provided.

It will thus be seen that by placing the valves in 25 a position to meet oncoming air to the cylinder, a dual purpose is accomplished; the valves are cooled, the cylinder and head are cooled. No less important is the fact that the change in engine design to accomplish this purpose has created a more compact engine with the cam shaft space being utilized from previously wasted space in the engine housing.

It will be apparent to those skilled in the art to 30 which my invention pertains, that various modifications and changes may be made therein without departing from the spirit of my invention or from the scope of the appended claims.

I claim:

1. A self-cooling internal combustion engine comprising a crankcase, a finned engine cylinder and a finned cylinder head, a crankshaft supported by said crankcase, intake and exhaust valves for said cylinder positioned adjacent the front end of said engine in a plane normal to said crankshaft and supported by the cylinder, an air moving device externally of said crankcase at the front end of said engine and comprising a blower mounted on the crankshaft and a blower housing enclosing said blower and having a discharge 35 opening adjacent the engine cylinder, and a partition in said blower housing and forming separate air passages extending directly from said blower to the discharge opening, thereby providing separate passages flowing separate streams of cooling air for respectively circulating over the

cylinder head and over the cylinder and valve mounting portions of said cylinder.

2. In an internal combustion engine having a finned cylinder and cylinder head, an air moving device driven by said engine, valves mounted in a housing adjacent said cylinder below said head in a plane normal to the crankshaft of said engine, an air cooling shroud comprising a shroud portion enclosing said air moving device and a second shroud portion enclosing said valve housing and finned cylinder and cylinder head, said second shroud portion enclosing said cylinder head and a major portion of said cylinder and having an outlet opening on the side of said cylinder opposite said valves, and provided with an air inlet opening on the valve side of said cylinder, and means within said first shroud portion providing separate air passages for respectively directing a portion of air to and around said valves, and a portion of air to and over said cylinder head.

3. In an internal combustion engine having a finned cylinder and cylinder head, an air moving device driven by said engine, valves mounted in a housing adjacent said cylinder below said head in a plane normal to the crankshaft of said engine, an air cooling shroud comprising a first shroud portion enclosing said air moving device and a second shroud portion enclosing said valve housing, the second shroud portion enclosing said

cylinder head and a major portion of said cylinder having an outlet opening on the side of said cylinder opposite said valves, and provided with an air inlet opening on the valve side of the cylinder communicating with said first shroud portion, and means within said first shroud portion providing separate air passages for directing respectively a portion of air to and around said valves, and a portion of air to and over said cylinder head, said air moving means mounted at the end of and driven by said crankshaft for passing air through said air passages.

EARL GINN.
